Patented Oct. 9, 1900.

H. F. NEUMAYER.
VALVE FOR HYDRANTS.

(Application filed June 18, 1900.)

(No Model.)

UNITED STATES PATENT OFFICE.

HORACE FALK NEUMEYER, OF MACUNGIE, PENNSYLVANIA.

VALVE FOR HYDRANTS.

SPECIFICATION forming part of Letters Patent No. 659,252, dated October 9, 1900.

Application filed June 18, 1900. Serial No. 20,739. (No model.)

To all whom it may concern:

Be it known that I, HORACE FALK NEUMEYER, a citizen of the United States, residing at Macungie, in the county of Lehigh and State of Pennsylvania, have invented a new and useful Valve for Hydrants, of which the following is a specification.

My invention relates to improvements in valves for hydrants and similar structures, the primary object of the invention being to provide an improved construction of the valve mechanism located at the lower end of the hydrant and arranged to control the flow of liquid through the hydrant from the main and to automatically drain the delivery-pipe to eliminate the possibility of freezing in the winter.

A further object of the invention is to eliminate the necessity for the employment of internal valves or other movable elements within the plunger or for piercing said plunger to form waste-ports, which features of construction not only increase the cost of manufacture, but render the hydrant more liable to derangement.

A still further object of the invention is to effect the closing of the controlling-valve before a drain-channel formed in the face of the plunger-cylinder is opened by the passage of the plunger-valve and to insure the closing of the channel before the controlling-valve is moved sufficiently from its seat to permit the ingress of water from the water-main to the interior of the hydrant, the primary features of the invention being directed to the accomplishment of the last-named objects.

With these several ends in view the invention consists in the construction and arrangement of hydrant-controlling and waste-valve mechanism hereinafter more fully described, illustrated in the accompanying drawings, and defined in the appended claims.

Referring to said drawings, Figure 1 is a central vertical section of the lower end of a hydrant, showing the plunger or controlling-valve closed and the drain-channel opened for the escape of water from the discharge-pipe; and Fig. 2 is a similar view showing the plunger in its raised position to open the plunger-valve and to close the communication between the drain-channel and the drain-

port. Fig. 3 is a detail sectional view of the cylinder.

Referring to the numerals of reference employed to designate corresponding parts in the several views, 1 indicates the main pipe or casing of a hydrant, upon the lower end of which is screwed the cylindrical plunger-casing 2, internally threaded at its lower extremity for the reception of the externally-threaded upper extremity of the foot-cylinder 3 of the hydrant. The foot-cylinder 3 is provided with an elbow or angle fitting 4, arranged for connection through a coupling 5 with the water-main or other source of supply. Above the elbow 4, through which is extended the right-angular passage-way 6, extends an upstanding annular valve-seat 7, which projects into the interior of the foot-cylinder 3, which latter defines what may be termed the "valve-chamber" 8 of the structure.

The usual discharge or delivery pipe 9 is disposed axially within the casing 1, and its lower extremity is screwed into the upper end of a hollow plunger 10, at the lower end of which is retained a heavy cup-shaped packing 11, movable within the chamber 8 and comprehending, in effect, a piston, inasmuch as said packing fits snugly within the chamber 8 to form a water-tight connection with the walls of said chamber. The piston 11 is retained against the lower end of the plunger by an annular retaining-flange 12, extending from and preferably integral with a hollow valve-plug 13, screwed into the lower end of the plunger and provided between its closed end 14 and the flange 12 with two or more ports 15, through which liquid inflowing from the water-main will find its way to the discharge-pipe when the controlling-valve 16, mounted upon the end of 14 of the valve-plug, is in the open position, as illustrated in Fig. 2 of the drawings. Thus when the controlling-valve is opened by the elevation of the plunger the water flows through the passage-way 6 to the chamber 8, thence through the ports 15 to the interior of the plunger, and is finally delivered through the pipe 9. It will appear, moreover, that when the plunger is depressed to present the controlling-valve to the valve-seat 7 the inflow of water to the

hydrant will be cut off, and the water remaining within the delivery-pipe will tend to flow back through the ports 15 to the interior of the cylinder 3. I have therefore provided 5 for the relief of the valve-chamber by forming in the interior wall thereof a vertical drain-channel 17, extending from a point below the piston 11 in the lowest position thereof to a point slightly above the piston in said position, 10 the upper end of the channel being defined by a horizontal extension 18 thereof. The vertical drain-channel 17 and its horizontal extension 18 constitute a T-shaped channel, the exit or discharge end of which defined 15 by the extension 18 is equal to or greater than the ingress-opening or inlet thereof, said inlet being defined by that portion of the channel 17 located below the piston 11 in its lowest position. Inasmuch as the particular form of 20 this drain-channel constitutes an important feature of the present invention, attention is called to its specific utility.

It will appear that while the channel 17 must be effective to carry off the water standing in the hydrant above the controlling-valve said channel must be closed by a very slight movement of the piston, as otherwise the escape of water through said channel and around the piston would be permitted upon 25 the opening of the controlling-valve to tap the hydrant. It is for this reason that I have formed the channel with the horizontal extension 18, because said channel will thus be given a discharge-opening equal to its inlet, 30 while at the same time permitting said discharge-opening to be entirely closed upon a very slight movement of the piston, thereby effecting the complete cut-off of the drain to prevent the escape in this direction of water 35 flowing into the hydrant from the water-main. 40

It is so absolutely necessary to prevent the escape of water through the drain from the water-main that I have not only sought to accomplish this end by the particular formation 45 of the drain-channel, but have constructed the controlling-valve in a peculiar manner, which appears to be novel and is certainly possessed of great practical utility. This valve I form by inlaying a circular compression-disk 19 in the lower end 14 of the valve-plug, the disk being of sufficient diameter to cause it to seat horizontally upon the end of the valve-seat 7. If this disk completed the construction of the valve, it will readily appear that the slightest movement of the valve-plug would open the controlling-valve, permitting water to flow into the cylinder 3 and through the drain-channel until the piston 11 should be raised sufficiently to completely 50 close the upper end of said channel. In fact, this undesirable flow would be maintained indefinitely, supposing the plunger to be elevated and retained in a position sufficiently 55 high to open the controlling-valve, but insufficient to close the upper end of the drain-channel. In view of these considerations I impose 60 against the under face of the disk 19 a metal 65

valve extension or plug 20, upon which is fitted from the under side a cup-shaped packing 21, held against the valve extension 70 20 by a washer 22, the disk 19, the extension 20, the cup-shaped packing 21, and the washer 22 being retained in proper assemblage by a screw 23, piercing each of said elements axially and extended into a threaded socket 24 75 in the end 14 of the valve-plug.

By reference to the drawings it will be seen that the upper edge of the packing 21 does not extend quite to the face of the disk 19, the intervening space being left to accommodate the slight elevation of the upper edge of 80 said packing as the latter is forced into and is compressed by the internal wall of the valve-seat 7, for which the valve extension constitutes, in effect, a stopper and provides 85 the controlling-valve with an active face auxiliary to the horizontal face of the valve defined by the under surface of the disk 19. It will now be seen that if the plunger is elevated the extension or stopper of the controlling-valve will maintain a water-tight closure within the valve-seat 7 until the piston 11 has completely closed the upper end of the drain-channel, at which time said plug or extension will be completely withdrawn from 95 the valve-seat and the water will find its way to the discharge-pipe in the manner hereinbefore described without the possibility of even the slightest escape through the drain-channel. 100

In like manner the valve extension will enter the valve-seat 7 and will effectually cut off the inflow of water before the valve proper has become seated and before the drain-channel is opened by the movement of the piston. 105 As soon, however, as the piston has opened the extension 18 of the channel both active faces of the controlling-valve will have become seated and the water remaining within the hydrant above the controlling-valve will escape to the interior of the cylinder 3 through the ports 15 in the valve-plug and will pass thence around the piston through the drain-channel and its extension to the interior of the plunger-casing and thence through the 115 drain-port 24 to the exterior of the hydrant. The drain-port 24 may be and preferably is protected by an integral cap or shed 25, cast upon the exterior of the casing 2. 120

From the foregoing it will appear that I have produced a simple and inexpensive construction and arrangement of the valve mechanism located at the lower end of hydrants or other devices of like character; but it should be distinctly understood that I reserve the right to effect such changes or modifications as may appear to me to be expedient from time to time, so long as no departure from the spirit of the invention is comprehended thereby. 125 130

What I claim is—

1. The combination with a cylinder having a passage-way for the induction of liquid, of a piston within the cylinder and having a

valve controlling the passage-way, said cylinder being provided with a drain-channel disposed in the direction of movement of the piston and with a transverse channel extension located immediately above the piston in the closed position of the valve.

2. The combination with a cylinder having a passage-way for the induction of liquid and a valve-seat, of a hollow plunger having means of communication with the interior of the cylinder, said plunger being provided with a piston fitting closely within the cylinder and with a valve extension disposed within the valve-seat, said cylinder being provided with a drain-channel extended below the piston and with a transverse channel extension disposed immediately above the piston in the closed position of the valve, said valve extension being capable of maintaining its connection with the valve-seat during the movement of the piston to close the channel extension.

3. The combination with a cylinder having a longitudinal drain-channel terminating at its upper end in a transverse channel extension extended in opposite directions from the channel, and an inwardly-extending valve-seat located at the lower end of the cylinder and surrounding a passage-way for the induction of liquid, a plunger having means of communication with the cylinder and provided with a piston fitting closely within the cylinder and with a controlling-valve located below the piston, said controlling-valve comprehending a valve extension extending within the valve-seat a distance at least equal to the movement of the piston necessary to effect the closing of the channel extension.

4. The combination with a cylinder having

an internal, longitudinal drain-channel terminating at its upper end in a transverse extension, and an upstanding valve-seat located at the lower end of the cylinder and surrounding a passage-way for the induction of liquid, a discharge-pipe located above the cylinder, a hollow plunger provided with a piston fitting closely within the cylinder, a separable valve-plug fast with the lower end of the plunger and provided with ports located below the piston, a valve inlaid in the end of the valve-plug and of sufficient dimensions to seat upon the valve-seat, said valve being provided with an axial valve extension extending into the valve-seat to a distance greater than the width of the channel extension, and a plunger-casing screwed upon the upper end of the cylinder and provided with a drain-port.

5. A valve-plug of the character described having a compression-disk inlaid in its end face, a metal valve extension disposed against said disk, a compressible cup-shaped packing disposed against the under side of said valve extension and having its edges slightly removed from contact with the disk, a metal washer disposed against the under face of the packing, and a screw piercing the washer, packing, valve extension and compression-disk and screwed into the valve-plug to retain said elements in a permanent assemblage.

In testimony that I claim the foregoing as my own I have hereto affixed my signature in the presence of two witnesses.

HORACE FALK NEUMEYER.
